WALTER A. SCHMIDT, OF LOS ANGELES, CALIFORNIA, ASSIGNOR TO INTERNATIONAL PRECIPITATION COMPANY, OF LOS ANGELES, CALIFORNIA, A CORPORATION OF CALIFORNIA.

METHOD AND APPARATUS FOR ELECTRICAL PRECIPITATION OF SUSPENDED PARTICLES FROM GASES.

Application filed December 15, 1920. Serial No. 430,891.

To all whom it may concern:

Be it known that I, WALTER A. SCHMIDT, a citizen of the United States, residing at Los Angeles, in the county of Los Angeles and State of California, have invented a new and useful Method and Apparatus for Electrical Precipitation of Suspended Particles from Gases, of which the following is a specification.

10 This invention relates to precipitation of suspended material, such as dust and fume, from gases by electrical action. In such operation as usually carried out the gases to be treated are passed between electrodes 15 maintained at high potential difference, certain of said electrodes being of such nature as to facilitate discharge of electricity into the gases and the action of the electrical field causes the suspended particles to be 20 collected on the electrodes.

It has been found that the operation of apparatus of this character is in some cases seriously interfered with by reason of the presence of ions in the gases supplied to 25 the electrical precipitating apparatus. This is particularly the case where the gases are received from furnaces in which the gases have been brought into contact with flames, or with bodies at high temperature, for example, in electric furnaces. In such cases 30 there are generally large numbers of ions present in the gases and these ions are generally not uniformly distributed in the gases, some parts of the gases having relatively 35 large numbers of ions while other parts of the gases may be comparatively free from ions, and, moreover, negative ions, or, in some cases, positive ions; may be preponderantly present in certain portions 40 of the gases and not in others. Owing to such uneven distribution of the ions there is considerable variation in the operation of electrical precipitating apparatus due, for example, to fluctuations in resistance of the 45 gaseous dielectric by reason of variations of the ions in different portions of the gases, it being understood that the greater the ionization the lower will be the electrical resistance of the gases. Such excessive and 50 variant ionization of the gases is not only objectionable in its direct results but tends to increase the difficulty by cumulative ac-

tion of the ionization on account of the rapidly moving ions tending to produce further ionization by collision with the gaseous molecules, thus increasing further the ionization, and correspondingly decreasing the resistance at parts which are already unduly ionized, with the result that fluctuations or variations in resistance of the gases tend to become accentuated and to still further interfere with maintenance of the desired electrical conditions in the precipitator.

With a gas of a given conductivity, it is possible to adjust the potential difference in an electrical precipitator so as to effect satisfactory precipitation without breaking down the gaseous dielectric but it is apparent that with gases fluctuating in resistance from time to time and from place to place in the gases, it is not possible to maintain at all times the operating potential difference best adapted to maximum precipitation on account of the liability to breaking down of the gaseous dielectric at parts where excessive ionization is presented.

The main object of the present invention is to provide for deionization or discharge of the gases to a sufficient extent to ensure effective operation of the electrical precipitating apparatus. This object is attained, according to my present invention, by subjecting the gases to the action of an electrostatic field produced between electrodes maintained at sufficient potential difference to cause translation or movement of the ions to such electrodes, with resultant removal of the ions from the gases, to a greater or less extent; the substantially or partially deionized gases then passing to the electrical precipitating apparatus.

The accompanying drawing illustrates apparatus suitable for carrying out my invention, and referring thereto:

Fig. 1 is a horizontal section of one form of such an apparatus;

Fig. 2 is a transverse section on line 2-2 in Fig. 1;

Fig. 3 is a transverse section on line 3-3 in Fig. 1;

Fig. 4 is a vertical section of another form;

Figs. 5 to 7 are diagrams showing modifications of the current connections.

In Figs. 1 and 2 I have illustrated my invention as applied in connection with a gas receiving flue or chamber 1, extending horizontally and conducting the gas through an electrical precipitator *b*. In said flue or chamber and in advance of such electrical precipitator I provide deionizing means *a* comprising electrodes 3 and 4 maintained at high potential difference, said electrodes 10 consisting, for example, of parallel vertical plates or screens of conducting material, such as metal, extending parallel to the direction of the gas flow. Electrodes 4 are grounded, for example, by connection to 15 the walls of the flue 1, which may be of metal or otherwise constructed so as to be conducting, and the opposing electrodes 3 are insulated, being mounted, for example, by frame 5 on insulators 6, and are connected 20 by wire 7 to a source of high electrical potential, for example, to a high tension alternating current circuit 8 energized from a low tension alternating current circuit 9 by a step-up transformer 10, a rectifier 11 25 being provided in said high tension circuit connections operating in synchronism with the alternating circuit to deliver rectified or unidirectional electrical current to the electrodes 3, such rectifier having a grounded 30 connection 12 for completing the circuit.

If required, potential controlling means, such as a resistance 13, may be provided in the connection from the high tension circuit to the electrodes 3. By the above described 35 means, or other suitable apparatus, sufficiently high potential difference is maintained between the electrodes 3 and 4 to generate strong electrostatic fields between the opposing electrodes. The electrodes being all of extended area and free from points 40 or edges, a purely electrostatic field is produced and substantially no electrical discharge takes place from the members 3 and 4.

The electrical precipitating apparatus *b* 45 may be of any usual or suitable construction, comprising, for example, collecting electrodes 15 formed as grounded vertical plates of relatively extended area and discharge 50 electrodes 16 formed as wires, rods or other conducting members of relatively small area mounted opposite the collecting electrodes and supported by an insulated frame 17, which is connected by wire 18 to a suitable 55 source of unidirectional high potential current, for example, to the circuit 8 leading to the rectifier above referred to, a resistance 20 being interposed, if required, for controlling the potential.

The operation of this form of my invention 60 is as follows:

The gases to be treated are assumed to be delivered to flue or chamber 1 from an electric furnace, blast furnace, smelting furnace, or other apparatus producing gases

containing suspended material and also containing ions in large quantity and in non-uniform distribution. Such gases pass between the opposing electrode members 3 and 4 of the deionizing means and are subjected 70 to the action of electrical fields maintained between said electrodes, with the result that the ions in the gases are caused to migrate or to be translated laterally of the direction of gas flow, by the force due to the electrostatic field and are collected or absorbed by the said electrodes. The gases passing to the electrical precipitator are, therefore, substantially or largely deionized, and the 75 distribution of the ions therein is also more uniform, with the result that operation of the electrical precipitator is rendered more uniform and efficient and the power consumption of the electrical precipitator is decreased, resulting in considerably higher 80 electrical efficiency.

The potential difference maintained in the deionizing apparatus may be different from that maintained in the electrical precipitator, for example, it may be considerably 90 higher on account of the fact that the electrodes in the deionizing means are all of extended area and without sharp curvature so that the tendency to electrical discharge is reduced to a minimum and comparatively 95 high potential difference can be maintained between the electrodes of the deionizer without breaking down the dielectric or causing excessive discharge. The deionizing means consumes a comparatively small amount of 100 current on account of such lack of discharge, the current consumption being mainly that due to the absorption of the electric charges of the ions present in the gases.

As shown in Fig. 5, the deionizing means *a* and the electrical precipitator *b* may be connected to separate high potential supply circuits 21 and 22, each provided with rectifier and energized by a step-up transformer in the manner above described, or as shown 110 in Fig. 6, the deionizer *a* and the electrical precipitator *b* may both be energized by direct connection to the same high potential circuit 23 without interposition of potential controlling resistances so that the same 115 potential difference is maintained on both of these devices. In some cases sufficient deionization may be effected by maintaining an alternating electric potential difference between the electrodes of the deionizer, the energizing connections thereof being made directly to an alternating high tension circuit, as indicated at 38 in Fig. 7. In view of the extreme mobility of the ions and their rapid movement under electrostatic 120 field forces such as may be produced between the deionizer electrodes under potential differences such as are usually maintained in electrical precipitators, it is possible, using alternating current of ordinary frequency 125 130

(60 cycle), to cause sufficient translation of ions to one or the other of the electrodes during such half wave of alternation to produce the required deionization.

- 5 In applying the invention to a horizontal flue treater the electrodes may be placed transversely of the flue, as indicated at 34 and 35 in Fig. 4, for the grounded and the high tension electrodes, respectively, the 10 high tension electrodes being mounted on an insulated frame 36 and the operation being the same as above described in connection with Figs. 1 to 3, except that the gases pass through instead of between the electrodes.
- 15 In this case, as in the form shown in Figs. 1 to 3, there may be more or less collection of suspended material as well as the ions on the electrodes of the deionizer and such suspended material is preferably removed from 20 time to time, or continuously, by shaking, jarring, or any other of the well known means for this purpose.

What I claim is:

1. The method of treating independently ionized gases containing suspended particles, which consists in initially subjecting such gases to the action of a purely electrostatic field having an extended sphere of action and of high intensity sufficient to largely deionize the gases and then independently subjecting the gas thus treated separately to the action of an electric discharge.
2. The method of treating independently ionized gases containing suspended particles which consists in initially subjecting such gases to the action of an electrostatic field of considerable extent between opposing electrodes of extended area maintained at high potential difference whereby the gases 35 are deionized to the required extent by the action of the electrodes, and then passing the gases through a separate and distinct electric field in which an electrical discharge

is produced, to separate the suspended particles from the gases.

3. The method which consists in initially passing an independently ionized gas containing suspended particles, through an extended electrostatic field, between non-discharging electrode surfaces of extended 50 area, maintained at high potential difference to cause translation of ions in the gases to the surfaces of said electrodes, and then subjecting the gases to electrical precipitating action in a distinct and separate field of 55 action.

4. An apparatus for treatment of independently ionized gases containing suspended material, comprising a deionizer, and a separate and distinct electrical precipitating means connected to receive the gases passing from the deionizer, said deionizer comprising non-discharging electrode means of extended area, and other non-discharging electrode means also of extended area, 60 opposing the first named electrode means defining therewith an electric field of considerable extent in the direction of the gas flow, and means for maintaining said electrodes at high potential difference.

5. Apparatus for the treatment of independently ionized gases containing suspended material, comprising electrodes constructed and arranged to produce an initial purely electrostatic field having an extended 75 sphere of action and having substantially no electric discharge when maintained at a high potential difference, a separate and distinct electric precipitator and means for passing the gas to be treated successively through 80 the sphere of action of said electrodes and the precipitator.

In testimony whereof I have hereunto subscribed my name this 7th day of December, 1920.

WALTER A. SCHMIDT.
